Patented Oct. 16, 1917.

UNITED STATES PATENT OFFICE.

EDWARD O. KRAEPELIN, OF BOTSFORD, CONNECTICUT.

COLLAPSIBLE EGG-CARRIER.

1,243,075.

Specification of Letters Patent. Patented Oct. 16, 1917.

Application filed October 26, 1916. Serial No. 127,735.

To all whom it may concern:

Be it known that I, EDWARD O. KRAEPELIN, a citizen of the United States, residing at Botsford, township of Newtown, county 5 of Fairfield, State of Connecticut, have invented an Improvement in Collapsible Egg-Carriers, of which the following is a specification.

This invention relates generally to packing and shipping cases, with more particular reference to cushioned containers for eggs and other fragile bodies, such as electric lamp bulbs, for example.

Where these bodies are themselves comparatively cheap in cost to the ultimate consumer, it is essential, of course, that the package or container in which they are placed, stored, handled and shipped, shall be itself relatively cheap in cost of production and delivery, so that the aggregate cost of the package and contents to the consumer shall not be excessive. At the same time, the construction of this package should be such as to insure a minimum of breakage 25 of the separated fragile bodies therein. Furthermore, in supplying a dealer with these packages, account must be taken of the fact that transportation charges are generally based upon the ratio between bulk and 30 weight, and these packages being necessarily very light in weight by comparison with their bulk, great economy results from a construction which enables the manufacturer to reduce bulk by packing these packages for 35 shipment in a "knocked-down" or collapsed condition, yet collapsed in such manner that they may be very easily and readily opened by the dealer for the insertion therein by him of the bodies or articles which are to be 40 handled or shipped and finally closed and sealed. Therefore, the present invention contemplates an exceedingly light and cheap package, the various parts of which may be 45 easily formed and assembled, which will amply cushion each individual fragile body contained therein without undue waste of space, which may be substantially completely collapsed for original packaging and 50 shipment, and which may be easily and readily opened by the dealer for the placing therein of the bodies to be shipped and just as easily and readily closed and sealed. Furthermore, this invention has in view a very 55 material increase in the capacity of a package of this character, without sacrifice of

the desired minimum ratio between bulk and weight.

My invention will be more readily understood by reference to the accompanying drawings, forming a part of this specification, in which—

Fig. 1 is a perspective view of a packing and shipping case embodying my invention, with the outer shell or case removed;

Fig. 2 is a transverse vertical section of one form of the interior casing shown in Fig. 1;

Fig. 3 is a perspective view of one of the interior containing jackets;

Fig. 4 is a view similar to Fig. 2 showing a slightly modified form of the construction illustrated therein;

Fig. 5 is a perspective view of the inner frame, as shown in Fig. 1, in a collapsed or knocked-down condition;

Fig. 6 is a perspective view of the package with the protecting outer shell or case thereon;

Fig. 7 is a transverse vertical section of Fig. 4, illustrating a modified form of the diagonally disposed dividing wall or partition;

Fig. 8 is a perspective view of the outer shell or case in a collapsed or knocked-down condition;

Fig. 9 is a detail view, in perspective, showing the interior containing jacket attached to the dividing wall, with the latter in a knocked-down condition, and

Fig. 10 is a perspective view of the bracing frame for the double dividing partition, as hereinafter described.

My improved package comprises an inner frame or casing in the form of a rectangular box 15, folded from a paste-board or preferably from what is known as a faced or double-faced corrugated paper blank, opposite sides thereof being open, whereby this casing or frame may be collapsed or "knocked-down" to substantially flat condition, as shown in Fig. 5. A wall or partition 16, which may be of either reasonably stiff paste-board or faced corrugated paper, as may be desired, divides the interior of the frame or casing 15, when expanded, diagonally into two longitudinally extending compartments. This partition or wall is retained in position by bending the end edges thereof around the edges of the top and bottom, respectively, of the side walls of the 110

frame or casing 15, and one of said side edges may be secured to the side wall of the frame by any suitable adhesive, as shown in Fig. 2, or both of said side edges may be left 5 free, as shown in Fig. 4. The frame 15 is so dimensioned as to reasonably snugly contain the individual jackets 19 in such number as that in which the contained articles are usually packed or sold, such as a half- 10 dozen or a dozen.

Each of the individual jackets 19 is formed from a small sheet of comparatively heavy paper, the blank from which it is shaped being substantially rectangular, all 15 though in cutting the form, flaps or flanges 20 are provided on opposite side edges extending from corresponding ends of said edges for a distance which approximates the width of the dividing wall or partition 16. 20 The blank is then curved to cause the lower ends of the flaps 20 to overlap, and to diverge from that point to form an acute angle, thus giving the receptacle a substantially cone-shaped configuration, as clearly 25 shown in Fig. 3. The material 21, at the bottom of the receptacle, is then pressed together and folded obliquely toward the side wall of the receptacle, the fold being so disposed as to form with the flaps 20 an angle which approximates the angle between the side wall of the casing 15 and the dividing partition 16 therein. The flaps 20 provide flat faces which, through the employment of any suitable adhesive, may now 30 be secured to the face of the dividing partition or wall 16, and the portion of the material 21 will be retained in a folded condition by the wall of the casing 15, as clearly shown in Fig. 4. The remaining jackets 35 having been similarly mounted, each thereof is now in condition to receive an egg, or other article, after which the top portion of the jacket is folded down upon itself to close the receptacle, as shown in Fig. 1, the 40 paper material being so folded as not to interfere with the slipping of the frame or casing 15 within the outer shell or case 22, although the resiliency of the folded material is such that the created friction will 45 yieldingly resist forces tending to withdraw the interior frame 15 from the outer shell or case 22 with which it has what may be termed telescopic connection.

In view of the fact that the wall or partition 55 16 divides the interior of the frame or casing 15 symmetrically into two triangularly-shaped compartments, it will be apparent that I may similarly mount upon the opposite face of the partition 16 a corresponding series of the individual jackets 19, thereby doubling the capacity of the package. Obviously, when the jackets 19 on one side of the package have been filled and closed, the package is turned over and the 60 jackets 19 in the other side thereof are simi- 65

larly filled and closed. These jackets are held in their closed condition by the outer shell or case 22, and it will also be apparent that in case both of the side edges 17 and 18 of the partition 16 are left free, the outer 70 shell or case 22 will also serve to engage these edges 17 and 18 and retain the partition 16 in place. I may give greater stability to the structure, however, without interfering with the collapsible property 75 thereof as a whole, by securing the side edge 17 of the partition 16 to the side wall of the frame 15 by any suitable adhesive, as shown in Fig. 2.

From the foregoing it is thought to be 80 apparent—as I have demonstrated to my own satisfaction—that I have provided a package for fragile bodies in which each individual body is amply cushioned against the effects of shocks and jars attendant upon 85 handling and transportation, and at the same time have provided a small package of relative large capacity, in which there is very little waste space, and in which the ratio between bulk and weight may be said 90 to be a minimum.

Furthermore, the containing frame in its entirety may be packed and shipped in collapsed or knocked-down condition. By folding the sides of the jacket 19 upon themselves, and then pressing toward each other diagonally opposite corners of the frame 15, the package may be reduced to substantially flat condition, as shown in Fig. 5, and this whether or not both or one only 95 of the side edges 17 and 18 of the partition 16 are unattached to a side wall of the containing frame. Obviously, the outer shell or case 22 may be collapsed to a substantially flat condition, as shown in Fig. 8, 100 and the fact that the inner frame and outer case must be separately collapsed and shipped is of no consequence in view of the fact that the two are necessarily separated when the contents of the package are being 105 placed therein.

Under what may be termed ordinary conditions, and with the individual jacket 19 made from proper stock, I have found that a single strip of paste-board or faced corrugated paper will satisfactorily answer all 115 purposes of the dividing wall or partition 16. However, where the container and its fragile contents is likely to be subjected to unusual shocks or jars, or frequent handling, particularly when eggs or other fragile bodies are packed in both compartments, I have found it safer to provide a double partition 23, as shown in Fig. 7. This double partition 23 is formed from a 120 single blank of either paste-board or faced corrugated paper, folded into the form of a rectangular frame of relatively shallow depth, and the meeting edges being suitably joined together to form a box having open 125 130

ends. In order to retain this frame in a substantially rectangular condition, I prefer to reinforce the same through the provision of another frame 24 which telescopes 5 and fits snugly in the frame 23 and the width of which is such that the sides of the double partition are held in a proper distance from each other. Obviously, when both compartments are filled, this double 10 wall forms a dividing partition which is more yielding and resilient than the single wall illustrated in Figs. 2 and 4, and affords much better protection to the contents of the container.

15 Of course, this double partition 23 will have to be removed in order to collapse the containing frame 15 so that the latter may be packed in a knocked-down condition. However, the individual jackets 19, secured 20 to each face of the partition 23, are removable therewith and are capable of being collapsed with the partition 23 to a form substantially such as that illustrated in Fig. 9. Of course, the reinforcing frame 24 will 25 have to be removed from the frame 23 before the latter with the individual jackets 19 can be collapsed, but it will be noted that the reinforcing frame 24 is also collapsible, so that while the structure in assembled 30 form may not be shipped in knocked-down condition, it may be readily separated into its component parts and each of said parts be collapsed as described.

Many modifications of minor details of 35 my improved case for eggs and other fragile bodies will doubtless readily suggest themselves to those skilled in the art to which it appertains, and I therefore do not desire to limit my invention to the specific construction herein shown and described.

I claim as new and desire to secure by Letters Patent:

1. A package of the character described comprising an elongated, substantially rectangular, collapsible box, open top and bottom, a diagonally disposed partition dividing said box longitudinally into two triangularly-shaped compartments, a row of individual, closable and collapsible containing jackets secured to said partition, the latter having at least one side edge thereof unattached whereby the entire structure may be endwise collapsed to substantially flat form, and a collapsible outer shell 50 or case to snugly contain said box, close the open top and bottom and prevent collapse thereof.

2. A package of the character described comprising an elongated, substantially rectangular, collapsible box, open top and bottom, a diagonally disposed partition dividing said box longitudinally into two triangularly-shaped compartments, a row of individual, closable and collapsible containing jackets secured to each side of said

partition, the latter having at least one side edge thereof unattached whereby the entire structure may be endwise collapsed to substantially flat form, and a collapsible outer shell or case to snugly contain said box, 70 close the open top and bottom and prevent collapse thereof.

3. A package of the character described comprising an elongated, substantially rectangular box, open top and bottom, a diagonally disposed partition dividing said box longitudinally into two triangularly-shaped compartments, said partition consisting of an open-ended rectangular frame of elastically yielding material provided with removable interior reinforcing means, and a row of individual closable containing jackets secured to said partition. 75 80

4. A package of the character described comprising an elongated, substantially rectangular box, open top and bottom, a diagonally disposed partition dividing said box longitudinally into two triangularly-shaped compartments, said partition consisting of an open-ended rectangular frame 90 of elastically yielding material provided with removable interior reinforcing means, a row of individual closable containing jackets secured to said partition, and a collapsible outer shell or case to snugly contain said 95 box, close the open top and bottom and prevent collapse thereof.

5. A package of the character described comprising an elongated, substantially rectangular box, open top and bottom, a 100 diagonally disposed partition dividing said box longitudinally into two triangularly-shaped compartments, said partition consisting of an open-ended rectangular frame of elastically yielding material provided 105 with removable interior reinforcing means, and a row of individual closable containing jackets secured to each of the side faces of said partition.

6. A package of the character described 110 comprising an elongated, substantially rectangular, collapsible box, open top and bottom, a removable, diagonally disposed partition dividing said box longitudinally into two triangularly-shaped compartments, 115 said partition consisting of an open-ended frame of elastically yielding material provided with a removable and collapsible interior reinforcing frame, a row of individual, collapsible and closable containing 120 jackets secured to said partition, and a collapsible outer shell or case to snugly contain said box, close the open top and bottom and prevent collapse thereof.

7. A package of the character described 125 comprising an elongated, substantially rectangular box, open top and bottom, a diagonally disposed partition dividing said box longitudinally into two triangularly-shaped compartments, and a row of indi- 130

vidual containing jackets secured to each of the faces of said partition, said jackets being formed from elastically pliable material curved and folded to provide substantially cone-shaped receptacles in extended length exceeding the height of said box and the free open end of each being closable by folding the material upon itself to lie within the boundary planes of said box, said box and its contents interfitting within a removable outer shell or case which when applied closes the open top and bottom of the former and prevents collapse thereof.

8. A package of the character described comprising an elongated, substantially rectangular box, open top and bottom, a diagonally disposed partition dividing said box longitudinally into two triangularly-shaped compartments, and a row of individual containing jackets secured to each of the faces of said partition, said jackets being formed from elastically pliable material curved and folded to provide substantially cone-shaped receptacles in extended length exceeding the height of said box and the free open end of each being closable by folding the material upon itself to lie within the boundary planes of said box, said box and its contents interfitting within a removable outer shell or case which when applied closes the open top and bottom of the former, the

entire structure—the attached parts collectively and the unattached parts individually—being collapsible to substantially flat forms.

9. A package of the character described comprising an elongated, substantially rectangular box, open top and bottom, a diagonally disposed partition dividing said box longitudinally into two triangularly-shaped compartments, said partition consisting of a removable, open-ended, rectangular frame of elastically yielding material provided with a removable interior reinforcing frame, and a row of individual containing jackets secured to each of the faces of said partition, said jackets being formed from elastically pliable material curved and folded to provide substantially cone-shaped receptacles in extended length exceeding the height of said box and the free open end of each being closable by folding the material upon itself to lie within the boundary planes of said box, said box, and its contents interfitting within a removable outer shell or case which when applied closes the open top and bottom of the former, the entire structure—the attached parts collectively and the unattached parts individually—being collapsible to substantially flat forms.

In testimony whereof I affix my signature.

EDWARD O. KRAEPELIN.
